UNITED STATES PATENT OFFICE

JULIUS RUWITCH, OF NORWAY, MICHIGAN

DISPLAY EQUIPMENT

Application filed February 18, 1929. Serial No. 340,778.

My invention relates to display equipment and more particularly to a novel device for displaying mattresses or the like articles.

It is the consistent practice in the trade where mattresses are displayed and sold to maintain a large area of the floor space for the purpose of displaying mattresses of various sizes and qualities. This practice results in a large waste of space, causes considerable dirt to be secreted within the mattresses, and after a short time the mattresses are virtually unfit for sale. This condition likewise causes considerable difficulty in properly displaying the mattresses upon a flat surface and necessitates considerable shifting from a pile.

One of the objects of my invention is to provide apparatus for supporting mattresses in a vertical position thus saving considerable floor space and insuring a large degree of sanitation.

Another object of my invention is to provide a device for vertically supporting a pair of mattresses which permits a ready inspection of a large portion of the surface of the mattresses without the necessity for the use of any great amount of physical exertion by the demonstrator.

My invention will be more readily understood by reference to the accompanying drawing in which

Fig. 1 is an end elevation of a device constructed substantially in accordance with my invention;

Fig. 2 is an enlarged end elevation of the supporting means showing two mattresses in dotted lines;

Fig. 3 is a side elevation of the supporting means for the mattresses, the mechanism being shown partly in section; and

Fig. 4 is a plan view of the clamping means for the mattresses.

By reference to the drawing it will be seen that I provide a cabinet 10 having the horizontally disposed metal frame members 11 of any desired cross section, constituting the supporting frame for the device hereafter to be disclosed. Secured at suitable spaced intervals to the frame members 11 are the outwardly extending supporting arms 12

of hollow construction and provided with a longitudinally extending slot in the lower face thereof. Disposed within the arms 12 are the rollers 13 containing the balls 13a suitably disposed on bearings 14 adapted to travel the length of the arms 12.

As best shown in Fig. 3 I prefer to utilize a pair of rollers at each end within the arms 12 connected by the bar 15, the lower portion of which protrudes below the longitudinal opening in the arm 12. At a point near the outer extremities of the connecting bar 15 I provide the depending arms 16 to which is secured the truss 17, comprising two parallel bars 18, 19 separated near the center thereof by the block 20. The truss is secured at its extremities to the depending arms 16. Thus the truss 17, arms 16 and bar 15 constitute the movable supporting carriage.

At the outer extremities of the truss 17 I provide the cross arms 21, 22 preferably passing through apertures in the bars 16 and 18, 19, for supporting the clamping bars 23, 24. The clamping bars may be preferably of common angle-iron and provided with a suitable aperture at the ends thereof for the admission of the cross arms 21 and 22. As shown in Fig. 4 the front portion of each of the clamping bars 23 and 24 is bent outward as indicated at 25 and 26 for a purpose to be later described. Thumb screws 27 and 28 or other means may be provided on the clamping bars to tighten the bars to the cross arms 21 and 22 when the mattress is installed.

In practice the supporting arms 12 are extended a substantial distance out from the inclosing cabinet so that where a plurality of mattresses are supported any desired pair of said mattresses may be readily pulled forward without disturbing the adjacent mattresses.

As illustrated this device contemplates the support of two adjacent mattresses, A, B shown in dotted lines. The truss 17 forms the inner backing for the clamping action of the bars 23 and 24 pressing against the mattress. By providing the truss as shown the inner bar is greatly strengthened and a better clamping action is had. The truss also

insures sufficient strength in case one mattress is removed.

As shown in Fig. 4 the outer portions 25 and 26 of the clamping bars 23 and 24 are bent slightly outward. This is for only a short length of the bar and towards the front and permits inspection of the full side of the mattresses for the whole length thereof and avoids pinching the mattresses in the edge, 10 which very frequently is found to injure the binding. If desired the thumb screws 27 on the one side or the thumb screws 28 on the opposite side may be loosened and a single mattress removed from the carriage without disturbing the adjacent supported mattress.

The device as herein disclosed presents a rigid construction and well adapted for the purpose disclosed. The mattresses are firmly held without material damage thereto in an upright and sanitary position available for ready inspection at all times with a minimum of physical exertion.

Modifications may be made in the construction herein illustrated and I do not wish to be limited except as indicated in the appended claims.

I claim:

1. The combination with a track and 30 wheeled carriage, of a vertical arm depending from the carriage, a horizontal supporting frame consisting of two oppositely bowed side pieces joined at their ends, the frame being fixed to the arm and of a length greater 35 than the width of a mattress, cross pieces fixed in the respective ends of the frame member, and bars adapted to slide on and be removably fixed to the cross pieces whereby two mattresses may be clamped and supported, 40 one on each side of said arm.

2. In a device of the class described the combination with a track and wheeled carriage, of a pair of depending supporting arms, a resilient truss member joining said 45 arms and being parallel to said carriage, a pair of cross arms joined to the respective ends of said truss member, and clamping bars 50 slideable on said cross arms, said clamping bars being substantially parallel in their effective positions on said cross arms.

3. In a display device adapted to support 55 a pair of mattresses in side by side relation, the combination of a track and a wheeled carriage operable therein, a pair of depending supporting members positioned on and near 60 the ends of said carriage, a resilient truss joining said members, said truss comprising a pair of strips joined at their extremities and separated at the center, a pair of cross arms fixed to the ends of said truss and disposed at right angles thereto, and a pair of clamping bars, the ends of which are adjustably slideable on said cross arms, said clamping bars being substantially parallel in their 65 final position of adjustment.

4. A mattress support and display device adapted to support a pair of mattresses in side by side relation, which comprises in combination a supported track having a continuous longitudinal slot in the bottom face thereof, a wheeled carriage adapted to travel in said track, a portion of said carriage projecting through the slot in said track, a pair of depending arms fixed to the ends of said carriage, a resilient truss fixed to said arms, a pair of cross arms fixed to the ends of said truss and extending at right angles thereto, and a pair of clamping bars, said clamping bars being adapted to be adjustably slideable on said cross arms and to lie in substantial parallelism in their final position of adjustment. 70 75 80

In testimony whereof I have affixed my signature.
